LIGHT ATTACHMENT

Frederick Raymond Sutherland and Charles Wheeler Bell, Harrodsburg, Ky.

Application June 14, 1932. Serial No. 617,198

1 Claim. (CL. 240—2)

This invention appertains to new and useful improvements in the art of illumination and more particularly to a novel light attachment for laundry irons.

5 The principal object of this invention is to provide a light attachment for irons which can be readily attached to a conventional iron so that a light will be thrown onto the work while the iron is in use.

10 During the course of the following specification, other important objects and advantages of the invention will become apparent to the reader.

In the drawings:—

Figure 1 represents a side elevational view of 15 an iron equipped with the novel attachment.

Fig. 2 represents a top plan view of the attachment of an iron.

Fig. 3 represents a horizontal sectional view substantially on line 3—3 of Fig. 1.

20 Fig. 4 represents a vertical sectional view taken substantially on the line 4—4 of Fig. 1.

Fig. 5 represents a fragmentary detailed sectional view taken substantially on line 5—5 of Fig. 2.

25 Fig. 6 represents a fragmentary detail sectional view disclosing another form of plug.

Fig. 7 represents an inside elevational view of the novel connector with which the plug shown in Fig. 6 is engageable.

30 Fig. 8 represents a perspective view of the conduit and support thereof.

Fig. 9 represents a diagrammatic view disclosing the electrical connections between the electrical devices involved.

35 Referring to the drawings wherein like numerals designate like parts, it can be seen in Fig. 4, that numeral 5 generally refers to the electric iron which includes the base 6 and the top shell 7.

40 Numeral 8 represents the di-electric carrier for the heating element, the ends of which are connected to the binding posts 9—10 by the members 11.

The binding posts 9 and 10 are located in the receptacle or the rear end of the shell 7 and into this is engageable the connector generally referred to by numeral 13 in Figs. 1 and 2.

45 As is clearly shown in Fig. 1, the connector 13 is made up of the di-electric sections 14—15, the section 14 being shown in Fig. 7, with the electrical conductors thereon, and removed from association with the section 15.

50 As can be seen in Fig. 7, numeral 16 represents a di-electric slider transversely disposed through the connector 14 and having the conductor bands 17—18 thereon. Numeral 19 represents a friction

55 spring for the slider 16. Numerals 20—21 repre-

sent conductor pins each of which terminate at one end at the slider 16 and at its opposite end, at the outer end of the section 14 in the form of a head 22. These heads 22—22 engage with the binding posts 9—10 in the receptacle 12 when the connector 13 is attached to the iron.

In the butt end of the connector 14 are the sockets 23—23 for receiving the plugs generally referred to by numeral 24 extending longitudinally in the section 14 and in contact with the slider 16 are the pins 25—26 with which the plugs 24—24 are engageable when inserted into the sockets 23—23. Conductors 27—28 extend

from the pins 25—26 and through the flexible conduit 29 which attaches to the sections 14 and 15. Each of the plugs 24 consists of a cup-like member 30 of di-electric material having a removable plug 31 at one end. Extending from the opposite end of the cup-like member 30 is the contact pin 32 which engages with the corresponding pin 25 or 26.

70 From the plugs 24 extend the wires 33 the wires extending through the tubular conduit 34 to connect with the socket 35, the socket 35 being carried by the spring clip 36 which attaches to the forward end of the handle 37 of the iron.

75 Numeral 38 represents a U-shaped support for the handle, the upper ends of the supports being attached suitably to the ends of the handle 37.

Fig. 8 represents a perspective view of the conduit and support thereof.

80 Fig. 9 represents a diagrammatic view disclosing the electrical connections between the electrical devices involved.

85 Referring to the drawings wherein like numerals designate like parts, it can be seen in Fig. 4, that numeral 5 generally refers to the electric iron which includes the base 6 and the top shell 7.

90 Numeral 8 represents the di-electric carrier for the heating element, the ends of which are connected to the binding posts 9—10 by the members 11.

The binding posts 9 and 10 are located in the receptacle or the rear end of the shell 7 and into this is engageable the connector generally referred to by numeral 13 in Figs. 1 and 2.

95 While the foregoing specification sets forth the invention in specific terms, it is to be understood that numerous changes in the shape, size and materials may be resorted to without departing from the spirit and scope of the invention as claimed hereinafter.

Having thus described our invention, what we claim as new is:—

100 In combination, a handle having a portion thereof adjacent one end reduced, a lamp, a clip having spring fingers, said fingers being adapted to engage the reduced portion of the handle while the clip proper engages the adjacent end of the handle, a plate extension on the clip and a lamp socket on the plate extension for holding the said lamp.

FRED RAYMOND SUTHERLAND.
CHARLES WHEELER BELL.
